UNITED STATES PATENT OFFICE.

JOHN H. WOLCOTT, OF CONCORD, MICHIGAN.

CORSET-FASTENING.

SPECIFICATION forming part of Letters Patent No. 699,359, dated May 6, 1902.

Application filed September 13, 1901. Serial No. 75,294. (No model.)

To all whom it may concern:

Be it known that I, JOHN H. WOLCOTT, a citizen of the United States, residing at Concord, in the county of Jackson and State of Michigan, have invented certain new and useful Improvements in Corset-Fastenings, of which the following is a specification, reference being had therein to the accompanying drawings.

10 This invention relates to improvements in corset busks and fastenings, the strips of elastic metal secured to the front edges of corsets and generally provided with means for securing said edges together.

15 The object of the invention is to provide elastic metallic busks for this purpose of such character that they can be made with great economy, utilizing substantially all of the strips of material initially provided for 20 their manufacture, and which shall when in place produce a smooth practically unbroken inner surface and outer surface for the finished corset at the edges.

Figure 1 is a perspective of the corset having busks of my improved form. Fig. 2 is a 25 cross-section through the edge portion of the corset, showing the two busks of the pair hooked together. Fig. 3 is a face view of a portion of the right-hand elastic busk 30 detached. Fig. 4 is a sectional view of the same on line IV, Fig. 3. Fig. 5 is a face view of the left-hand busk before the tongues have been turned to form the hooks. Fig. 6 is a similar view after the hooks have been 35 formed. Figs. 7 and 8 are sectional views of the busks united, taken through the hooks and between the hooks, respectively.

In the drawings, A indicates the right-hand busk as a whole, and B the left-hand, reference being made to "right hand" and "left hand" merely as a matter of convenience.

The busk A is formed of a flat piece of elastic steel of uniform width from end to end, and with the exception of the small slots or 45 apertures for the hooks of the busk B can be manufactured without any loss of material. The said slots or apertures are indicated by a, being relatively long and narrow, their longer axes being parallel to the length of 50 the busk. They may be of any suitable length, though I have found that a half-inch,

approximately, is the best for ordinary purposes.

The busk B is manufactured from a steel strip and without loss of any of the material 55 whatsoever. It is so shaped that the one half of it (considering it divided longitudinally)—that is, the portion at b—lies in one plane, while the half or portion at b' is in another, they being "offset" somewhat relatively to 60 each other to form a longitudinal shoulder, as shown at b². At b³ b³ short slots are cut transversely of the steel strip, and the tongues b⁴ between these cuts or slots are turned upward and backward to form the hooks b⁵. 65 The distance of the extreme hook b⁵ from the neighboring ends of the busk B and the distances from each hook to the next correspond, respectively, to the distances of the apertures a in the busk A from the ends and from each 70 other.

Busks having incident to them features of the kind described can be manufactured at the very minimum of cost and with the utmost economy of material.

75 The busks B can be made successively from a long strip or coil of elastic steel. The tongues b⁴ are turned up to form the hooks b⁵ after cutting the slits either by suitable devices in the same machine which effects the shaping 80 and cutting or in a separate mechanism or by hand, if preferred.

It will be seen that these busks can be manufactured with great rapidity and with the utmost of economy, there being no loss whatever of any of the initially-provided metal except the insignificant waste due to forming the slots or apertures a. After the busks are completed they are then covered with suitable easing material, as at F, and secured to 90 the fabric G of the corset.

Fig. 2 illustrates the fact that the offset at b³ in the busk B insures that the hook parts b⁵ shall not project beyond the lines of the outer surface of the corset. The hooks b⁵ 95 normally lie in the planes of the part b of the busk B, and, moreover, these hooks are inside of the side edges at b⁶. The busk A, when the two busks are united, lies substantially in the plane of the part b of the busk B, opposite the shoulder E². In this respect the busk B differs from any that have been 100

used or suggested, so far as I know, in the earlier ones the hooks being projections extending beyond and to points outside of the side edge of the busk; but, as stated, in my 5 construction each hook lies entirely between the side edges b^6 and b^7 of the busk, and this enables me to provide a firm fastening of the two busks together, as it prevents the free hinging action incident to those which 10 have the hooks projecting from one of the side edges, the parts at b^8 , which are between the hooks, lying behind or back of the busk A when the corset is in use and substantially in one plane from the edge b^6 to the shoulder b^2 .

15 What I claim is—

1. In a corset-fastening, the combination of the two busks, one having a continuous longitudinal shoulder, b^2 , and the parts of the busk at the opposite sides of the shoulder 20 lying in different planes, and one of said parts having hooks integral therewith bent toward and opposing said shoulder, and the other busk having apertures near its edge to receive said hooks, whereby it will lie with said 25 edge against and lapping over the nearer part of the former busk, opposite said shoulder, and in substantially the same plane with the farther part of the other busk.

2. In a corset-fastening, the combination 30 of the two busks, one having a continuous

longitudinal shoulder b^2 , and the parts of the busk at the opposite sides of the shoulder lying in different planes, and one of said parts having hooks integral therewith formed within the edge of the busk bent toward and opposing said shoulder, and the other busk having apertures near its edge to receive said hooks, whereby it will lie with said edge against and lapping over the nearer part of the former busk opposite said shoulder and 35 in substantially the same plane with the farther part of the former busk, substantially as set forth.

3. A fastening device for a corset, consisting of a busk having a series of apertures, 45 and an opposite busk having the portions b , b' offset or in different planes forming the shoulder b^2 , the part b extending continuously in one plane from the edge to the shoulder b^2 , the hooks b^5 , situated entirely between 50 the side edges of the busk, and the portions b^8 of the part b' between the hooks lying in one plane from the edge b^6 to said shoulder b^2 , substantially as set forth.

In testimony whereof I affix my signature 55 in presence of two witnesses.

JOHN H. WOLCOTT.
